(57) **CLAIM**

The ornamental design for a drive-through vehicle-scanning archway, as shown and described.

DESCRIPTION

FIG. 1 shows front perspective view of a drive-through vehicle-scanning archway;

FIG. 2 shows a front view of the entrance to the drive-through vehicle-scanning archway of FIG. 1;

FIG. 3 shows a rear view of the exit from the drive-through vehicle-scanning archway of FIG. 1;

FIG. 4 shows a left side view of the drive-through vehicle-scanning archway of FIG. 1;

FIG. 5 shows a cross-sectional view of the inside of the right side of the drive-through vehicle-scanning archway of FIG. 1;

FIG. 6 shows an inside upward-looking view of the drive-through vehicle-scanning archway of FIG. 1;

FIG. 7 shows a front perspective view of an embodiment of the drive-through vehicle-scanning archway of FIG. 1;

FIG. 8 shows a rear view of the exit from the embodiment of the drive-through vehicle-scanning archway of FIG. 7;

FIG. 9 shows a cross-sectional view of the inside of the right side of the embodiment of the drive-through vehicle-scanning archway of FIG. 7; and,

FIG. 10 shows an inside upward-looking view of the embodiment of the drive-through vehicle-scanning archway of FIG. 7.

1 Claim, 10 Drawing Sheets
